UNITED STATES PATENT OFFICE.

ROBERT S. COHOON, OF ORLANDO, FLORIDA, ASSIGNOR TO SOUTHERN CEMENT MACHINE COMPANY, OF ORLANDO, FLORIDA, A CORPORATION OF FLORIDA.

CONCRETE-BLOCK MACHINE.

Application filed March 18, 1922. Serial No. 544,711.

To all whom it may concern:

Be it known that I, ROBERT S. COHOON, a citizen of the United States, residing at Orlando, in the county of Orange and State of Florida, have invented certain new and useful Improvements in Concrete-Block Machines, of which the following is a specification.

My invention relates to concrete block machines and has for one of its objects the provision of simple and efficient means for striking off the top of the material in the form.

A further object is the provision of simple and efficient means for using the material struck off from the top of one block for use in forming the next block.

Another object is the provision of simple and efficient means for maintaining the parts of the form or mold in rigid positions during the forming of the block.

Another object is the provision of simple and efficient means for closing the core opening in the block when it is desired to form solid blocks.

Another object is the provision of means for automatically locking the sides of the mold upon moving the cores to operative positions.

Other objects will appear hereinafter.

An embodiment of my invention is illustrated in the accompanying drawings forming a part of this specification, and in which—

Fig. 1 is a plan view of a concrete block machine embodying my invention;

Fig. 2 is a similar view, but showing some of the parts removed to expose the frame of the device;

Fig. 3 is a closure used for closing the core openings;

Fig. 4 is an end elevation of the device;

Fig. 5 is a fragmental enlarged section showing details of the construction;

Fig. 6 is a fragmental section showing the core opening closure in position; and

Fig. 7 is an adjustable locking plate used in the construction.

Referring more particularly to the drawings, I have indicated a frame made up of end pieces 8 and 9 secured together by longitudinally extending bars 10 and 11. The

bars 11 form guides upon which tri-angularly shaped frames 12 and 13 are mounted, substantially like the mountings in United States Patent No. 1,241,288, dated September 25, 1917, granted to S. D. Lindsay. At adjacent corners of the frames 12 and 13 are pins or bolts 14 which engage slots 15 of a hand lever 16. The latter is pivoted as at 17 intermediate the pins 14 so that swinging of the lever from its full line to its dotted line positions of Fig. 2 will move the outer parallel sides 18 of the tri-angular frames 12 and 13 from their full to their dotted line 65 positions of said figure.

On one of the rods 10 is pivoted an angular member 19 which carries a plate 20, and the latter forms the bottom of the mold during the forming of the block. The two angular members, one adjacent each end of the mold, are provided with tongue and grooved connections 21 with a pallet 22. In the construction of blocks, the blocks when formed, are left on pallets 22 so that for each block 75 a new pallet 22 must be placed on the members 19. The pivotal mounting of the members 19 provides means for easily moving the block from the position in which these parts are disposed for making the block, such as 80 indicated in Fig. 4, to the position where the block is removed from the machine, which is indicated in Fig. 5.

The ends 23 of the mold are secured to the members 18, as clearly indicated in Fig. 2, 85 by means of cap screws 24, or any other desirable means. The back 25 of the mold is rigidly attached to the ends 8 and 9 of the frame and it is provided with a number of core openings 26 corresponding to the number 90 of cores used in the machine. The plate 25 therefore does not move and is the only part of the mold which is not moved to remove a block.

Back of the plate 25 and near the ends 95 8 and 9 of the frame are two guide rods 27, one of which is indicated in the drawings. Mounted upon the guide rods 27 is a core holder 28. To the core holder 28 is secured a plurality of cores 29. The cores 29 may 100 be secured by means of screws 30 to their mountings 28, or in any desirable manner. On the plate 25 is a lip 31 which facilitates guiding the cores into the openings 26. Two

levers 32 are pivoted on one of the rods 10, as clearly indicated in Figs. 4 and 5, and are connected to the core mounting 28 by means of links 33. The upper ends of levers 32 are connected together by a rod 34. On the rod 34 are mounted cams 35 adapted to engage cams 36 on the members 19 so that when the latter are in their position shown in Fig. 4 the cams 35 will engage the cams 36 and hold the members 19, 20 and 22 in rigid relation with the frame. The cams 35 are adjustably mounted by means of set screws 37, or their equivalent, so as to vary the relation between the cams 35 and 36 when desired.

On adjacent sides of the levers 32 are frames 38 which are adapted to engage cam lugs 39 on the end plates 23 of the mold so that when the levers 32 are in their positions indicated in Fig. 4 the frames 38 will be in engagement with cam lugs 39 rigidly locking the end plates 23 against spreading. When desired, plates 40 may be attached to the bottom and top edges of frames 38 by means of screws 41 and slots 42, or their equivalent, so that pressure which can be applied to lugs 39 by the levers 32 may be varied.

Extending away from the top edge of the mold with one edge resting on the plate 25 is a plate 43. This plate provides a table upon which the concrete extending above the top of a mold, when forming a block, can be struck off by means of the hopper 44 mounted in guides 45 on frame ends 8 and 9.

When it is desired to form solid blocks and the cores 29 are not to be used, openings 26 can be closed by plates 46 mounted on rods 47 by placing the members 46 in openings 26 and passing the rods 47 through the molds, as clearly indicated in Fig. 6. A nut 48 or other desirable means may be used to hold the members 46 in place. When solid blocks are made it is desirable to disconnect the core molds 29 from the levers 32. This can be done by simply unscrewing bolts or screws 33' appearing in Figs. 1, 4 and 5. When it is desired to form hollow blocks again the screws 33' are again placed in their positions indicated so as to connect the connecting links 33 with the levers 32.

In use, the parts of the machine are placed in the positions indicated in Fig. 4 and the concrete placed in the hopper 44 and tamped down in the usual manner. When the form is full, hopper 44 is moved back in its guides 45 over the plate 43 to strike off the top of the block. The levers 32 are then raised to their positions indicated in Fig. 5 to unlock the ends 23 and the latter are moved to their full positions in Fig. 2 by manipulating lever 16 to free the ends 23 from the block. The plate 20 and pallet 22 are then tipped over on the pivot rod 10 to their positions indicated in Fig. 5

where the pallet 22 with the block is slipped off the members 19 and taken away from the machine for drying. In arranging the device for another block, a new pallet 22 is placed on members 19 and the latter moved about their pivots to the position indicated in Fig. 4. The ends 23 are then moved to their closed positions by levers 16 and levers 32 moved down again to lock said ends of the mold. The hopper is then drawn from its position of Fig. 5 to its position of Fig. 4 to bring the material dragged over on plate 43 back over the mold where the material drops into the latter to be used in the next block.

I claim:

1. A concrete block machine comprising a mold having movable sides; cams on said sides; and adjustable cams adapted to engage the first-mentioned cams for locking the movable block sides against spreading.

2. A concrete block machine comprising a mold having ends adapted to be moved away from each other and a bottom and one side adapted to be moved about a pivotal point adjacent a longitudinal corner of the mold; and levers having cams thereon adapted to engage said movable sides and ends to hold the latter against movements away from each other.

3. A concrete block machine comprising a mold having a bottom wall and a side wall pivotally mounted and end walls slidably mounted; cores adapted for movement into said mold; levers attached to said cores for moving the latter into said mold; and cams mounted on said levers for connection with said side and ends of the mold for holding the latter against spreading.

4. A concrete block machine comprising a mold having sides with a core opening in one of said sides; and a closure for said core opening adapted for connection with said core for holding the core opening closure in said opening.

5. A concrete block machine comprising a mold having a side with a core opening in the latter; a plate of substantially the size of said core opening; a rod attached to said plate and extending through said core adapted to hold said plate in said core opening against the adjacent end of said core; and adjustable means on said rod for locking said plate tightly against said core.

6. A concrete block machine comprising a frame; a mold on the frame having parallel movable end walls; a shaft journaled in the frame; two spaced levers fixed on said shaft and adapted for movement across the remote sides of said end walls; lugs on said end walls; and frames on the levers adapted to engage said lugs and hold the end walls against movement away from each other.

7. A concrete block machine comprising

a frame; a mold on the frame having parallel movable end walls; a shaft journaled in the frame; two spaced levers fixed on said shaft and adapted for movement across the remote sides of said end walls; lugs on said end walls; and plates adjustably mounted on the adjacent sides of said levers and

adapted to engage said lugs for holding the end walls against movements away from each other.

10

In testimony whereof I have signed my name to this specification on this 28th day of February, A. D. 1922.

ROB'T. S. COHOON.
